Arthur B. Guinnip

C. Snow & Co.

UNITED STATES PATENT OFFICE.

ARTHUR B. GUINNIP, OF SENECA FALLS, NEW YORK, ASSIGNOR OF ONE-HALF TO A. M. NELSON, OF SAME PLACE.

BICYCLE-PUMP.

SPECIFICATION forming part of Letters Patent No. 636,522, dated November 7, 1899.

Application filed June 3, 1899. Serial No. 719,281. (No model.)

To all whom it may concern:

Be it known that I, ARTHUR B. GUINNIP, a citizen of the United States, residing at Seneca Falls, in the county of Seneca and State of New York, have invented a new and useful 5 Bicycle-Pump, of which the following is a specification.

This invention relates to pumps, and particularly to hand-pumps for use in inflating 10 bicycle-tires and the like.

The object of the invention is to provide means for connecting several pump-cylinders, so as to form a single compact and useful device.

15 To this end the invention consists in the combination and arrangement of parts, as will be hereinafter more fully described, shown in the accompanying drawings, and particularly pointed out in the appended 20 claims.

In the drawings, Figure 1 is a perspective view of the device. Fig. 2 is a vertical longitudinal sectional view thereof. Fig. 3 is a horizontal sectional view taken through the 25 base.

Corresponding parts are designated by like reference characters in all the figures of the drawings.

Referring to the accompanying drawings, 30 1 and 2 designate pump-cylinders, respectively, which are connected together by a base 3 and a head 4. The base and head are each formed from a block of wood and are clamped together upon the cylinders by means

35 of a longitudinal bolt 5. The pump-cylinders are spaced apart a suitable distance, and the bolt is arranged between the same, having its head 6 seated in a recess 7, formed in the under side of the base, so that the latter may

40 have a flat underneath side and may rest firmly upon the floor or ground. The bolt passes upward through the base and through the head 4 and is provided with a nut 8 upon its upper end, whereby the head 4 and base

45 3 may be clamped tightly upon the cylinders. It will be noted that the opposite ends of each cylinder are beveled or sharpened, as at 9, so that said sharpened ends cut into the wooden base and head under the action of the clamp- 50 ing-bolt 5 and form an air-tight joint between

the cylinders and the head and base, respectively.

Each cylinder is provided with a plunger-rod 10, passing loosely through the head 4 and connected together above the same by 55 means of a suitable handle 11. The head thus forms a guide for the rods in the operation of the pump. At its lower end each rod is provided with a suitable plunger 12, and the base within the respective cylinders is 60 dished or recessed, as at 13, to receive the lower ends of the plunger-rods at the extent of their downward movement. As shown in Fig. 3, convergent passages 14 extend from each recess 13 to a common point and communicate with a single upright discharge tube or nipple 15. The usual flexible tubing is fitted to the tube 15, whereby the air is conveyed to the tire in the common manner.

By the construction and arrangement herein described the two pump-cylinders are firmly connected together by a simple and substantial frame, forming a complete and compact device which discharges the air from two cylinders through a single outlet. By removing 70 the nut 8 the frame may be taken apart and the several parts of the device may be cleaned or replaced if broken or damaged. The operating parts of the pumps may be of any preferred form and more than two cylinders may 75 be employed, the invention residing solely in the frame whereby the cylinders are connected together.

Changes in the form, proportion, size, and the minor details of construction within the 80 scope of the appended claims may be resorted to without departing from the spirit or sacrificing any of the advantages of this invention.

Having thus described the invention, what is claimed is—

1. In combination with two or more pump-cylinders having beveled or sharpened upper and lower ends, a base and a head between which the cylinders are adapted to be held, and a bolt or the like arranged between the 95 cylinders, connecting the head and base and adapted to clamp the latter upon the cylinders, whereby the ends of the latter cut into the base and the head forming an air-tight joint therebetween, and are connected to- 100

gether in a single device, substantially as shown and described.

2. In combination with two or more pump-cylinders, a base, and a head between which
- 5 the cylinders are adapted to be held, and a bolt or the like arranged between the cylinders, connecting the base and head, and adapted to clamp the latter upon the cylinders and connect the same together in a single device,
- 10 the plunger-rods being adapted to pass loosely through the head as a guide, and a handle connecting the plunger-rods above the head, substantially as shown and described.
3. In a pump, the combination with two or
- 15 more cylinders, of a base having recesses for each of the cylinders, and convergent passages communicating from the respective recesses to a common point, a tube or nipple at

the convergent point of the passages, a head for the opposite ends of the cylinders, means 20 for clamping the base and the head upon the opposite ends of the cylinders, plungers working in each cylinder, a plunger-rod for each plunger, working loosely through the head, and projecting beyond the latter, and a handle connecting the projecting ends of the plunger-rods, substantially as and for the purpose set forth.

In testimony that I claim the foregoing as my own I have hereto affixed my signature 30 in the presence of two witnesses.

ARTHUR B. GUINNIP.
